DESIGN FOR A SALT TABLET DISPENSER

Robert A. Kelly, East Pittsburgh, and Paul C. Perrin, Pittsburgh, Pa., assignors to Mine Safety Appliances Company, Pittsburgh, Pa., a corporation of Pennsylvania

Application September 27, 1937, Serial No. 71,825

Term of patent 14 years

To all whom it may concern:

Be it known that we, Robert A. Kelly and Paul C. Perrin, citizens of the United States, residing at East Pittsburgh, in the county of Allegheny and State of Pennsylvania, and Pittsburgh, in the county of Allegheny and State of Pennsylvania, respectively, have invented a new, original, and ornamental Design for a Salt Tablet Dispenser, of which the following is a specification, reference being had to the accompanying drawing, forming a part thereof.

Fig. 1 is a top plan view, Fig. 2 is a front view, Fig. 3 is a side view, Fig. 4 is a bottom view, and Fig. 5 is a rear view of a salt tablet dispenser embodying our new design.

We claim:

The ornamental design for a salt tablet dispenser as shown.

ROBERT A. KELLY.
PAUL C. PERRIN.
